UNITED STATES PATENT OFFICE.

CHARLES STAFFORD, OF CHICAGO, ILLINOIS, ASSIGNOR OF ONE-THIRD TO
EDWARD STAFFORD, OF SAME PLACE.

DEVICE FOR CONVERTING MOTION.

SPECIFICATION forming part of Letters Patent No. 614,141, dated November 15, 1898.

Application filed March 12, 1898. Serial No. 673,651. (No model.)

To all whom it may concern:

Be it known that I, CHARLES STAFFORD, a citizen of the United States, residing at Chicago, in the county of Cook and State of Illinois, have invented certain new and useful Improvements in Devices for Converting Motion; and I do declare the following to be a full, clear, and exact description of the invention, such as will enable others skilled in the art to which it appertains to make and use the same.

My invention relates to improvements in mechanical movements for converting motion; and the object is to provide a simple device of this character whereby the movement of a car may be utilized through the medium of my device to operate the switch-points, switch-frogs, crossings, crossovers, signals, safety-gates, and the numerous devices of a similar character employed on a modern railway system.

To this end the invention consists in the construction, combination, and arrangement of the device, as will be hereinafter more fully described, and particularly pointed out in the claims.

The accompanying drawings show my invention in the best form now known to me; but many changes in the details might be made within the skill of a good mechanic without departing from the spirit of my invention, as set forth in the claims at the end of this specification.

The same reference characters in the drawings indicate the same parts of the invention.

Figure 1 is a perspective view of my improved mechanical movement, showing its application to a railway-track. Fig. 2 is a top plan view. Fig. 3 is a transverse section on the line 3 3 of Fig. 2. Fig. 4 is a transverse section on the line 4 4. Fig. 5 is a cross-section on the line 5 5. Fig. 6 is a longitudinal section through the center of the shaft.

1 denotes a rock-shaft formed with the integral journals 2, by means of which it is mounted in suitable bearings, and in the present instance these bearings are the brackets 4 and 5, fixed to the outside rail 6. A crank-arm 7 is fixed to the outer end of said shaft, and

from this arm a rod 8 connects with a crank 9 on a vertical shaft 10, mounted in the semaphore or signal-lantern stand 12.

13 represents a grooved quadrant formed integral with the shaft 1 and concentric with its axis, and 14 denotes a chain or flexible wire rope having one end fixed to the quadrant and at its other end connected to a spring-actuated lever *a*, fulcrumed on a bolt *b* midway between the rails, and from the opposite ends of said lever the rods *c* and *d* extend to the frogs *e* and *f*, respectively, so as to simultaneously shift them when the lever *a* is operated.

The shaft 1 is formed with a radial flange 15, the central portion 16 of which extends from the dotted line *x* to the dotted line *z*, and between these two points the outer edge of said flange lies in a plane parallel with the axis or median line 17 of the shaft, and from the point *x* to the contiguous end of the shaft the flange 15 is spirally curved for about one-quarter of a circle, more or less, so as to form a continuation of the longitudinal flange 15 to that end of the shaft. From the point *z* the flange 15² is spirally curved in the reverse direction to the crank end of the shaft.

The inner plane longitudinal edge 18 of the flange 15 extends in an opposite direction beyond the axial line 17 of the shaft, and this edge of the flange 18 is formed with an eye 19 to receive the outer end of the rod 20, the inner end of which is pivoted to the switch-frog 21, the rod 20 passing through a guide-bracket 22, and 23 denotes a spiral spring 85 encompassing the rod 20 between said bracket and switch-frog, the tension of which is exerted to retain the shaft 1 in its normal position, as shown in Fig. 1, so that when a car is approaching in the direction of the arrow 90 the tread of the wheel will ride over the spiral flange 15² and rotate the shaft one-quarter of a turn on its axis until the wheel comes to the parallel flange 15, which holds the shaft in this position. Then as the wheel passes 95 over the spiral flange 15² it allows the shaft to resume its normal position, as above described.

It will be noted by reference to Fig. 5 that when the shaft 1 is in its normal position the 100

- eye 19 of the flange is in line with the axis of the rod 20 and the axial line 17 of the shaft, so that no amount of pressure applied to said rod in the direction of the arrow will change 5 the position of the shaft. At the same time the least movement of the shaft on its axis will reciprocate the rod longitudinally, and this feature is especially valuable where the inner end of the rod is connected to the switch-frog, as shown, as it effectually locks the frog in that position, so as to prevent its accidental displacement or, in fact, any movement of said frog except when the shaft is operated by the car-wheels.
- 15 Of course it will be understood that the shaft is rotated on its axis by the car-wheel, as hereinbefore described. The switch-rail and the signal are simultaneously operated at the same time as the switch-frog.
- 20 While I have shown my device as applied to a railway signal and switches, I do not wish to confine myself to such use, as it is obvious that it is adapted to a variety of other applications.
- 25 Having thus fully described my invention, what I claim as new and useful, and desire to

secure by Letters Patent of the United States, is—

1. A mechanical movement comprising as an element an axially-journalized shaft having 30 a radial flange formed with a central plane section extending longitudinally parallel with the axis of said shaft and terminating in spirally-curved sections forming continuations of said plane section, as and for the purpose 35 set forth.

2. A mechanical movement comprising as an element an axially-journalized shaft having a radial flange formed with a central plane section extending longitudinally parallel with 40 the axis of said shaft and terminating in reversely-arranged spirally-curved sections forming continuations of said plane section, as and for the purpose set forth.

In testimony whereof I have hereunto set 45 my hand in presence of two subscribing witnesses.

CHARLES STAFFORD.
